CLAIM

The ornamental design for a display screen or portion thereof with graphical user interface for patient timeline navigation, as shown and described.

DESCRIPTION

FIG. 1 is a front view of a first image in a sequence of a display screen or portion thereof with graphical user interface for patient timeline navigation showing our new design; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; and, FIG. 7 is a front view of a seventh image thereof.

The outermost broken line rectangular indicates a boundary of a display screen or a portion thereof and forms no part of the claimed design. The broken lined text, patterns, and characters form no part of the claimed design. The appearance of the animated images sequentially transition from

(Continued)

FIG. 1 to FIG. 7. The process or period in which one image transitions to another forms no part of the claimed design.
